UNITED STATES PATENT OFFICE.

HERBERT M. PURDY, OF MADISON, NEBRASKA.

AUTOMATIC RAILROAD GATE.

Application filed January 13, 1928. Serial No. 246,546.

This invention relates to a railway crossing closing mechanism, and has for its object to provide, in a manner as hereinafter set forth, a mechanism of such class including a pair of gate members and operated by a train when approaching a crossing to position the gate members in a manner to close the crossing to prevent vehicles or pedestrians from travelling over the track until the train has cleared the crossing, under such conditions reducing accidents to a minimum.

A further object of the invention is to provide, in a manner as hereinafter set forth, a spring controlled railway crossing closing mechanism operated by a train when approaching the crossing for closing the latter and maintained in position to prevent the vehicles or pedestrians from travelling across the track until the train has cleared the crossing whereby the possibility of accidents is reduced to a minimum.

Further objects of the invention are to provide, in a manner as hereinafter set forth, a spring controlled railway crossing closing mechanism which is comparatively simple in its construction, strong, durable, thoroughly efficient in its use, automatic in its action, readily installed with respect to a track and crossing, and comparatively inexpensive to set up.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view of a railway track, partly broken away, showing the adaptation therewith of a spring controlled railway crossing closing mechanism in accordance with this invention and with the mechanism also broken away.

Figure 2 is a view similar to Figure 1 in side elevation.

Figure 3 is a fragmentary view in side elevation and upon an enlarged scale illustrating the spring controlled pull elements of the gate members shifting cables.

Figure 4 is a section on line 4—4 Figure 1.

Figure 5 is a fragmentary view in elevation illustrating a pair of pulleys for a shifting cable and a support for the pulleys.

Figure 6 is a fragmentary view in top plan, partly in section, of the cable pulling means.

Figure 7 is a fragmentary view in perspective of the depressible spring controlled pull members for the gate members shifting cables.

Referring to the drawings in detail 1 and 2 denote a pair of track rails providing a railway track and 3 indicates a crossing. Adjacent the outer side of each of the track rails, is arranged a hinged gate member and which are indicated at 4, 5. The hinges of each of the gate members are indicated at 6. The gate members are normally in a flat position relative to the crossing 3, and when the mechanism is operated by a train, the gate members are shifted to vertical position or substantially to vertical position and such arrangement of the gate members will close the crossing. The gate members will be arranged in closing position with respect to the crossing 3 until after the train has cleared the crossing. The gate member 4 at one outer corner thereof is provided with an eye 7 and the gate member 5 at one outer corner thereof is provided with an eye 8 and to said eyes are connected shifting cables which are employed for elevating or swinging the gates 4, 5 to vertical position. The gates 4, 5 return to normal position by gravity when the pull upon the gate shifting cables is released. The gates 4, 5 are simultaneously operated to closing position with respect to the crossing. The gate shifting cable which is connected to the eye 7 of the gate member 4 is indicated at 9 and the gate shifting cable which is connected to the eye 8 of the gate member 5 is indicated at 10. That part of the crossing 3 at the track can be formed of platform or any suitable material, and cut away at 11, 12 for the reception of the gate members 4, 5 when these latter are in inactive position and the hinges 6, that is the inner leaves thereof are anchored to the platform. The gate members 4, 5 are of a length to close the crossing 3 to an extent to prevent the passage thereover, at the track, of pedestrians and vehicles. The width of each of the gate members 4, 5 can be as desired.

Mounted on the ties 13, at a point an appropriate distance from one side of the

crossing 3, and at the outer side of each track rail, but in close proximity thereto, is a pair of spaced supports 14, 15 arranged in lengthwise alignment and each of which has its inner end positioned upon a tie which is indicated at 16. The inner ends of the supports 14, 15 are spaced from each other and are arranged in alignment with opposed walls of a socket 17 which is provided in the top of the tie 16. The supports 14, 15 at points between the ties are formed with vertically disposed openings 18 and in each opening 18 is secured the lower end of a vertically disposed combined guide and retaining rod 20. The rods 20 are spaced from the track rail and progressively increase in height from the outer to the inner end of a support 14 or 15. Arranged over the support 14 is a depressible pull member 21 and arranged over the support 15 is a depressible pull member 22. The pull members 21, 22 extend at an upward inclination from the outer to the inner ends of the supports 14, 15. The outer end of each pull member is formed with a lengthwise extending slot 23 and each pull member is positioned in close proximity to a track rail. The pull members are not only guided by the rods 20, but are also maintained in close position to the track rail thereby. The outer end of each pull member is slidably connected against the outer side of the head of the track rail and for this purpose a bolt 24 is used and which is carried by the track rail and extends through the slot 23. The bolt 24 is of materially less diameter than the length of the slot 23. The inner or upper end of each pull member is reduced as indicated at 25, and seats upon a spring controlled suspended block 26 formed with a vertically disposed web 27 to which the reduced upper ends 25 of the pull members are connected by the bolts 28. The reduced upper ends 25 of the pull members are arranged in spaced relation. The upper ends of the pull members 22 can cant on the block 26. The outer end of the block 26 is formed centrally thereof with an extension 29, provided with an elongated oval shaped slot 30. Seated in the socket 17 is a combined controlling and suspension spring 31 for the block 26. The spring 31 has its upper end secured to the block 26 by a bolt 32, and the latter extends through the end 25 of the pull member 21. The lower face of the block 26 is formed with a socket 33 for the upper end of the spring 31. The bottom edge of the upper end 25 of the member 21 seats directly upon the block 26. The bottom edge of the upper end 25 of the member 22 is spaced from the block 26. The reduced upper ends 25 of the pull members form shoulders or stops 34 which abut against the sides of the block 26, whereby the latter is retained between the pull members. The normal position of the pull members is such as to extend above the tread of the track rail from the outer to the inner ends of such members. The inner ends of said members are the upper ends thereof. The extended or elevated position of the pull members is had by and against the action of the controlling spring 31. The pull members are engaged and depressed by the treads of the wheels of the rolling stock travelling over the track rails.

Slidably and pivotally connected to the extension 29 is a pull lever 34, having a bifurcated inner end 35, carrying a pin 36. The inner end 35 of the lever 34 straddles the extension 29 and the pin 36 extends through the slot 30 formed in said extension whereby a sliding and a pivotal connection is had between the inner end of the pull lever 34 and the extension 29. Positioned outwardly of and spaced from the supports 14, 15 is a pair of spaced, opposed standards 37, each provided at its upper end with a bearing 38. The bearings 38 oppose each other and mounted therein is a pivot 39 for the pull lever 34. The pivot 39 is positioned at a point between the vertical median and the inner end of the lever 34 and the latter is disposed at right angles with respect to the pull members 21, 22 and arranged substantially in a plane which would intersect the opposed upper inner ends of the pull members. The outer end of the pull lever 34 is provided with an eye 40. The two pair of standards are mounted upon bases or platforms 41 which project outwardly from each of the track rails. In Figure 1 one of the pull levers is indicated at A and the other, at B and the pull cable 9, which co-operates with the gate member 4, is connected to the eye 40 of the pull lever A, and the pull cable 10, which co-operates with the gate member 5, is connected to the eye 40 of the pull lever B. Arranged on the platform are supporting brackets 42, 43, provided with pulleys 44, 45 respectively. Arranged on the platforms 41 in proximity to the gate members 4, 5 are supporting brackets 46, 47. Each of said brackets includes an upstanding arm 48 provided at its top with a grooved pulley 49. Each bracket is furthermore provided at its lower portion with a grooved pulley 50. The pulleys 49 and 50 are disposed at right angles with respect to each other. The bracket 46 co-operates with the pull cable 9 and the bracket 47 co-operates with the pull cable 10. The pull cables travel under the pulleys carried by the brackets 42, 43, around the pulleys 50 carried by the brackets 46, 47 and over the pulleys 49 carried by the brackets 46, 47 and then extend to the gate members 4, 5. When the two pair of depressible pull members are lowered by the wheels of the rolling stock, the pull levers 34 are moved on their pivots in a manner whereby the

outer ends of said pull levers will be elevated, carrying the pull cables therewith and elevating the gate members to the dotted line showing in Figure 4. After the wheels 5 of the train have passed or cleared the pull members, the action of the springs 31, will release the pull cables or provide a slack therein, and the gate members will then automatically move to inactive position by 10 gravity.

The mechanism provides means for shifting the gate members, automatically to active position, as a train approaches the crossing and the gate members will remain 15 in such position until the wheels of the train clear the pull members, after which the gate members will assume their normal or inactive position.

When the mechanism is employed in connection with a single track, a mechanism 20 will be arranged adjacent each side of the road crossing, one mechanism to be actuated when the train is travelling in one direction and the other mechanism actuated when the 25 train is travelling in the opposite direction. The mechanism can also be arranged in a manner to be used in connection with a double track.

It is thought the many advantages of a 30 crossing gate closing mechanism, in accordance with this invention, can be readily understood and although the preferred embodiments of the invention are as illustrated and described, yet it is to be understood 35 that changes in the details of construction can be had which will fall within the scope of the invention as claimed.

What I claim is:

1. A railway crossing gate closing mechanism comprising a pair of hinged gate members normally in a lowered position, pull cables connected therewith for elevating said members, a pair of spring controlled suspended blocks, a pair of oppositely disposed normally elevated pull members connected at their inner ends to each of said blocks and adapted to be depressed by the wheels of a train, a pull lever extending from and pivotally and slidably connected to each block, and means for connecting said pull cables to the outer ends of said levers whereby when said pull members are depressed the pull cables will be drawn in a direction to elevate the gate members.
2. A railway crossing gate closing mechanism comprising a pair of hinged gate members normally in a lowered position, pull cables connected therewith for elevating said members, a pair of spring controlled suspended blocks, a pair of oppositely disposed normally elevated pull members connected at their inner ends to each of said blocks and adapted to be depressed by the wheels of a train, a pull lever extending from and pivotally and slidably connected to each block, means for connecting said pull cables to the outer ends of said levers whereby when said pull members are depressed the pull cables will be drawn in a direction to elevate the gate members, a set of grooved pulleys for each of said cables, and means for slidably connecting the outer end of each of said pull members to a track rail.
3. A railway crossing gate closing mechanism comprising a pair of hinged gate members normally in a lowered position, pull cables connected therewith for elevating said members, a pair of spring controlled suspended blocks, a pair of oppositely disposed normally elevated pull members connected at their inner ends to each of said blocks and adapted to be depressed by the wheels of a train, a pull lever extending from and pivotally and slidably connected to each block, means for connecting said pull cables to the outer ends of said levers whereby when said pull members are depressed the pull cables will be drawn in a direction to elevate the gate members, and a set of grooved pulleys for each of said cables.
4. A railway crossing gate closing mechanism comprising a pair of hinged gate members normally in a lowered position, pull cables connected therewith for elevating said members, a pair of spring controlled suspended blocks, a pair of oppositely disposed normally elevated pull members connected at their inner ends to each of said blocks and adapted to be depressed by the wheels of a train, a pull lever extending from and pivotally and slidably connected to each block, means for connecting said pull cables to the outer ends of said levers whereby when said pull members are depressed the pull cables will be drawn in a direction to elevate the gate members, and a set of grooved pulleys for each of said cables, one of the pulleys of each set positioned above the remaining pulleys of the set.
5. A railway crossing gate closing mechanism comprising a pair of hinged gate members normally in a lowered position, pull cables connected therewith for elevating said members, a pair of spring controlled suspended blocks, a pair of oppositely disposed normally elevated pull members connected at their inner ends to each of said blocks and adapted to be depressed by the wheels of a train, a pull lever extending from and pivotally and slidably connected to each block, means for connecting said pull cables to the outer ends of said levers whereby when said pull members are depressed the pull cables will be drawn in a direction to elevate the gate members, and means for slidably connecting the outer end of each of said pull members to a track rail.

6. A railway crossing gate closing mechanism comprising a pair of hinged gate members normally in a lowered position, pull cables connected therewith for elevating said members, a pair of spring controlled suspended blocks, a pair of oppositely disposed normally elevated pull members connected at their inner ends to each of said blocks and adapted to be depressed by the wheels of a train, a pull lever extending from and pivotally and slidably connected to each block, means for connecting said

pull cables to the outer ends of said levers whereby when said pull members are depressed the pull cables will be drawn in a direction to elevate the gate members, a set of grooved pulleys for each of said cables, one of the pulleys of each set positioned above the remaining pulleys of the set, and means for slidably connecting the outer end of each of said pull members to a track rail. In testimony whereof, I affix my signature hereto.

HERBERT M. PURDY.
